UNITED STATES PATENT OFFICE.

SAM R. SMITH, OF LOS ANGELES, CALIFORNIA, ASSIGNOR OF FIVE ONE-HUNDREDTHS
TO PAUL G. HOFFMAN, OF PASADENA, CALIFORNIA.

FLYING-MACHINE.

1,139,820.

Specification of Letters Patent. Patented May 18, 1915.

Application filed January 30, 1914. Serial No. 816,642.

To all whom it may concern:

Be it known that I, SAM R. SMITH, a citizen of the United States, residing at Los Angeles, in the county of Los Angeles and State of California, have invented a new and useful Flying-Machine, of which the following is a specification.

My invention relates to improvements in flying machines, and the object of my invention is to provide a flying machine which in starting a flight may lift itself from the surface in a substantially vertical direction and in ending a flight may descend in a similar manner, without the gliding start or stop, as is necessary in the common type of such machines.

Another object is to provide a means for the simultaneous opening and closing of a plurality of revoluble planes.

Another object is to provide a means whereby a plurality of coacting revoluble planes may be simultaneously opened on the down stroke, and closed on the up stroke.

Another object is to provide a means whereby said planes may be adapted to open and close at any desired position around their axes.

Another object is to provide a means whereby a heavier than air vehicle composed of a plurality of revoluble planes, may be forwardly or upwardly propelled by changing the angle at which said planes will open and close.

Another object is to provide a heavier than air vehicle having a low center of gravity.

Another object is to provide a vehicle having an auxiliary means for stabilizing the vehicle and retarding it in its descent in the event of the stoppage of the engine in mid-air.

Another object is to provide a heavier than air vehicle having a series of collapsible, extensible and revoluble planes adapted to completely revolve wide open or totally extended so that when about to alight the descent of the machine will be retarded by extending the planes by means of an air valve located at or near the driver's seat.

Other objects may appear in the subjoined detailed description.

My invention consists primarily in that form of heavier than air vehicles adapted to rise directly from the ground in a sub-

stantially vertical direction and comprises a plurality of revoluble elements arranged in pairs or sets, there being an equal number of said elements on each side of the center of the vehicle all of said elements being parallel and adapted to rotate in the same direction; each of said elements comprising a frame fixed to a shaft and having arms radiating from said shaft on each end of the frame, the arms on one side being in the same transverse plane with those on the other end, and a plurality of collapsible planes being mounted between the opposite arms. The arms are hollow and are suitably secured at their inner ends to a cylinder, the number of said cylinders being equal to the number of arms, and said cylinders being cast integral with a cylinder head adapted to rotate with the arms and provided at the outer face with a smooth surface adapted to contact with a normally stationary, but adjustable valve collar. Suitable air ports are provided in the cylinder heads and the valve collars for the admission and emission of air to and from the cylinders.

The details of my invention are disclosed in the subjoined description in which similar reference numerals refer to like parts throughout the several views of my invention on the drawings, in which:

Figure 1 is a perspective view of my device, with details eliminated. Fig. 2 is a side elevation. Fig. 3 is a cross section on the line x^3-x^3 , Fig. 4 of the air valve mechanism. Fig. 4 is a cross section on the line x^4-x^4 , Fig. 3 of the same, showing the arm and the wing operating mechanism. Fig. 5 is an enlarged sectional view of the arm and the wing operating mechanism. Fig. 6 is a view showing the manner of securing the wing stays to the strand. Fig. 7 is a plan view of the same, but showing, additionally the manner of securing the wings to the stays. Fig. 8 is a sectional elevation of the same. Fig. 9, is a perspective view of one series of planes and the revolving arms, the details of the valve collars and cylinders being omitted. Fig. 10 is a lateral section of Fig. 5 on the line $x^{10}-x^{10}$.

The main frame consists of the horizontal members 1, the vertical members 2 and suitable guy strands 3 located at convenient positions around the frame. The auxiliary plane 4 is secured to the horizontal members

1 of the top of the main frame in any suitable manner, and is used to maintain an even keel of the machine when in flight, or in the event of a sudden stoppage of the engine or motor, will retard the descent of the vehicle owing to the resistance of the air, and like a parachute will serve to maintain the vehicle in an upright position. At the bottom of the main frame are secured the 5 horizontal cross members 5, 5', 6 and 6' to which are suitably secured the bearings 7, having revolvably mounted therein the shafts 8.

The sub-frame 9 depends from the main 15 frame and is provided with a suitable floor, which may be inclosed by a screen 9', and on which is mounted the engine or motor 10 and the driver's seat 11. Beneath the sub-frame 9 are the runners 12 which are 20 connected with the sub-frame by the coil springs 13, by means of which when alighting, the vehicle is cushioned against the impact with the ground or surface upon which the vehicle alights. I may equip the runners with wheels, not shown, if it is desired, or the manner of securing the same to the frame may be changed to suit varying 25 conditions.

On the inner ends of the shafts 8 and 30 fixed thereto are the sprockets 14, and on one of these shafts or on a secondary shaft 16, as shown in Fig. 2 is placed the sprocket 15, which is connected with a similar sprocket 17 on the engine shaft by the chain 35 18 and similar chains 19 connect the sprockets 14 with the driving sprocket 15, thus imparting motion to all of the shafts 8, the sprockets and chains being so arranged that all of the shafts rotate in the same direction.

On each end of the shafts 8 and immediately inside of the bearings 7 are loosely fitted the valve collars 20 which have the inwardly projecting flanges 21 and the concentric ports 22 and 23, the former being an intake port and the latter an exhaust, and secured to the flange 26 of the bearing 7 are the studs 25 adapted to engage the slots 25' in the valve collars 20 and on these studs 50 are the springs 27 adapted to bear against the valve collar 20, and hold them normally away from the bearings 7. The bearings 7 and the collars 20 are so positioned on the shafts 8 as to allow of a sliding backward 55 and forward on the shafts 8 of the valve collar for purpose of self adjustment. Revolvably mounted on the shafts 8 and adjacent to the valve collars 20 are the cylinder heads 28, the outer ends 29 thereof being 60 adapted to fit tightly and revolvably in the recess in the valve collars 20 formed by the flanges 21, and extending outwardly and radially from this head are the cylinders 30, having on the outer ends the contracted necks 31 over which are fitted and to which

are tightly secured the hollow arms 32, the cylinders and arms on both ends of the shafts being exactly opposite each other.

The pistons 33 are slidably mounted in the cylinders and have secured thereto, the piston rods 34 slidably mounted in the neck 31 and provided outside of the neck and in the hollow arms with the springs 35, and the arms 35'.

In the face 29 of the cylinder head are 75 the circular ports 36 at right angles to and connecting the cylinders 30 and adapted to register with the valve ports 22 and 23, in the valve collar 20.

The air supply tube 37 may be connected 80 with an air storage tank or compressor in any suitable manner. In both ends of the arms 32 are revolvably mounted the sheaves 38 on the pins 39, and passing over the sheaves are the endless strands 40 to which 85 are secured at regular intervals, by means of the U bolts 41, the ends of the cross bars 42 adapted to slide in suitable slots 43 in the sides of the arms 32, an equal number of the cross bars being secured to the upper and lower sides of the endless strand 40, and the upper cross bars being substantially over the position occupied by the lower cross bars. A fabric plane 44 is secured 90 at one side to the cross bar on the top side of the strand and on the other side to the cross bar on the lower side of the strand, the manner of securing the planes 44 to the cross bars consisting of passing the ring 45 through the perforations 46 in 100 the cross bars 42 and through the metal eyes 47 in the wings and then clamping the ends of the rings together. The planes 44 are collapsible and adapted to be folded as 105 shown in Fig. 5 on the upstroke, and to be extended or spread when the arms are on the downstroke, in their revolution.

All of the valve collars 20 are connected 110 with the lateral rod 48 by means of the arms 50, and the rod 48 is connected with the hand lever 51 on the side of the seat 11 by means of the arm 52. The steering wheel 53 is secured in a suitable manner to the floor of the sub-frame or the seat 11, and operably connected with the steering vane 115 54 on the top of the main frame, by means of the steering rod 55.

In operation, when the engine or motor is started the valve collars being normally set so that the exhaust ports therein will 120 register with the ports in the cylinder heads at the instant when the arms in their revolution around the shafts begin the down stroke, the air will be released from the cylinders 30 and by means of the springs 35 acting against the arms 35', which slide in the hollow arms 32 and are secured to the strands 40 at their forward ends, the pistons will slide inwardly in the cylinders, and by means of their connec- 125 130

tion with the strands will cause the strands to move on the sheaves 38, thus separating the cross bars 42 and spreading the planes 44, which will remain spread until the bottom of the stroke has been reached and the intake ports in the valve collars and the cylinder heads register, when air will be admitted into the cylinders, cause the pistons to slide outwardly, and by moving the strands on the sheaves cause the planes to collapse or fold up so as to offer no resistance to the air on the upstroke. The ports in the valve collars are elongated concentrically so that area enough is provided to insure the absolute filling or evacuation of the cylinders with the air from the tank when the cylinders revolve rapidly.

The hand lever on the side of the driver's seat is in a neutral position when the valve collars are so set that the cylinders will take air at the beginning of the upstroke and exhaust at the beginning of the downstroke, so that when the clutch on the engine is thrown in gear with the driving sprockets, and the arms begin to revolve, the tendency of the vehicle is to lift from the surface in approximately a vertical direction, and this action will continue until it is desired to move forward or backward, when upon shifting the hand lever 51 in a forward or backward direction, as the case may be, the movement of the lever will cause the valve collars 20, by means of the rods 48 and the arms 52 to revolve on the shafts a part of a revolution in proportion to the movement of the lever 51, and this movement of the valve collars changes the point at which the air will be admitted to and exhausted from the cylinders, and serves to regulate the speed and angle of flight of the vehicle, which is at all times, proportional to the movement of the valve collars. It should be understood that all of the valve collars are coacting and are operated simultaneously.

The engine and driving mechanism being located at the exact center of gravity of the vehicle, and said center of gravity being below the planes of the vehicle, an even keel will at all times be maintained, and should the engine stop when the vehicle is in mid-air, the large auxiliary plane on the top of the vehicle will cause the vehicle, parachute like, to drop to the surface in an easy manner, and will also serve to balance the vehicle in flight. The collapsible planes, while serving primarily as a lifting and propelling means, also become automatically extended or spread, when the engine is stopped and the air is expelled from the cylinders when a by-pass valve (not shown) at or near the driver's seat is turned off so that the air tank is disconnected from the cylinders, in which case the springs 35 will extend or spread the planes 44 and so hold them regardless of the relative position of

the valve ports and valve collars, thus serving jointly with the auxiliary plane to retard the descent of the machine in case of accident.

It is obvious that I may use any number of revoluble arms or any number of collapsible planes between the arms, or I may use a somewhat different construction without departing from the spirit of my invention.

I am aware of certain patents relating to this type of vehicle none of which embody my principle of collapsing the planes or spreading them, and I desire to claim broadly my invention in this particular.

Having described my invention, what I claim is:—

1. A flying machine having a series of revoluble collapsible planes arranged in pairs and series of pairs, which when caused to revolve will raise said machine from the surface in a substantially vertical direction, compressed air means for collapsing and spring means for spreading said planes.

2. A flying machine having a series of revoluble collapsible planes arranged in pairs, and series of pairs, operably connected to a series of compressed air actuated pistons by which said planes may be collapsed, and a series of springs by which said planes may be spread, and means for revolving said planes.

3. A flying machine having a series of revoluble collapsible planes arranged in pairs, and series of pairs, compressed air means for collapsing said planes, and spring means for spreading said planes automatically when the engine is accidentally stopped, whereby the descent of said machine may be gradually accomplished.

4. A flying machine having a series of revoluble collapsible planes arranged in pairs and series of pairs, spring means for spreading and compressed air means for collapsing said planes alternately and regularly, at opposite points in their revolution, and means attached to or near the operator's seat whereby the spreading or collapsing of said planes may be regulated or the point in their revolution at which said spreading or collapsing occurs may be changed at the will of the operator to produce a forward or upward movement of said machine.

5. A flying machine having a series of revoluble collapsible planes arranged in pairs and series of pairs, spring means for spreading and compressed air means for collapsing said planes alternately and regularly at opposite points, in their revolution, and means whereby said spreading and collapsing points may be regulated or moved around the axis of said planes to produce a forward, backward, upward or downward direction of flight.

6. A flying machine having a series of

revoluble collapsible planes arranged in pairs and series of pairs, spring means for spreading and compressed air means for collapsing said planes alternately and regularly at opposite points in their revolution, in combination with means for revolving said planes and a stationary auxiliary plane

horizontally disposed above said revoluble planes as described.
